Specification of Letters Patent.

Patented Jan. 7, 1913.

Application filed June 4, 1906. Serial No. 320,089.

To all whom it may concern:

Be it known that I, FREDERICK W. COLE, of Newton Highlands, county of Middlesex, State of Massachusetts, have invented an improvement in Whistle-Blowing Apparatus, of which the following description, in connection with the accompanying drawings, is a specification, like characters on the drawings representing like parts.

This invention relates to whistle blowing apparatus, especially adapted for use in connection with fire-alarm systems, and has for its object to improve the construction of the same to the end that the whistle-valve will be operated to start the blasts immediately after the circuit is opened or the impulses received, and that the blasts will continue for uniform periods of time.

It is herein designed to construct and arrange the device so that the blast will be started as soon as the circuit is opened or the impulse received, that there may be no delay, and also that the blast will continue for a predetermined period of time, regardless of the length of time the circuit remains open, or its normal condition remains changed, and that all parts of the valve actuating mechanism shall come to rest promptly at the end of the blast, thereby enabling the apparatus to start each blast from a state of rest. By constructing the device to operate in this manner the signal which is sounded by the whistle will follow the exact spacing of the signal which is transmitted by the signal box, and will be clear and distinct so as to be easily counted. Furthermore, an apparatus constructed in accordance with this invention, will operate rapidly, which at the present time is an important factor.

Figure 1 shows in plan view a whistle blowing apparatus embodying this invention. Fig. 2 is a side elevation of a portion of the apparatus shown in Fig. 1, the parts being in their normal positions of rest. Fig. 3 is a vertical section of a portion of the apparatus shown in Fig. 1, taken on the dotted line 3—3, the parts being in their normal positions of rest. Fig. 4 is a sectional detail showing the parts in the position they will occupy just after the whistle-valve has been opened. Fig. 5 is a vertical section of a portion of the apparatus shown in Fig. 2, taken

on the dotted line 5—5, the parts being in their normal positions of rest. Fig. 6 is a detail showing particularly the restoring-device for the actuating mechanism for the whistle valve. Fig. 7 is a detail showing particularly the restoring device for the controlling-lever. Fig. 8 is a detail of the governor which I employ for the time-controlled mechanism.

α represents an electro-magnet which is included in or operated by the fire-alarm circuit, and is adapted to respond directly or indirectly to the impulses of the signals which are transmitted by any usual or suitable fire-alarm signal box.

α' represents the armature of the electro-magnet α , which is borne by a pivoted armature-lever α^2 , in any usual manner. The circuit of the electro-magnet α is designed to be normally closed.

A controlling-lever b is secured to a shaft b' , having its bearings in the side plates of the apparatus. One end of said lever engages the armature-lever α^2 , and is thereby normally held in elevated position when the armature is attracted, but will be disengaged therefrom when the armature is retracted, and when disengaged, will be drawn down by a spring b^3 , which is connected to it by a link b^4 , or otherwise, and when thus drawn down, the shaft b' bearing it will be turned on its axis or rocked. A short arm c is secured to said shaft b' , some distance from the controlling-lever b , which extends therefrom beneath a pin c' , projecting laterally from an ear c^2 on a locking-lever c^3 , which is secured to a pivot-shaft c^4 , having its bearings in the side plates of the apparatus. The locking-lever c^3 has a limited up and down movement, and to provide for thus limiting its movement a finger c^5 extends downward from it, between two pins c^6 , c^7 .

The locking-lever c^3 is lifted by the short arm c engaging and lifting the pin c' , and when permitted said lever falls by gravity. The locking-lever c^3 engages the upper end of an arm d extended radially in an upward direction from a hub d^2 , which is mounted loosely on a shaft d' arranged below the shaft b' , and a short arm d^20 also extends radially from said hub in a downward direction, to the extremity of which a spring d^2 is attached, which acts to hold the

arm d in engagement with the end of the locking-lever. When the locking-lever is lifted said arm d will be disengaged and will be moved forward quickly by the spring d^2 .
 5 A tripping prop d^4 is formed on or secured to said hub d^3 . Said prop is employed to hold the operating-device for the whistle-valve, and which is herein referred to as the actuating-mechanism for the whistle-valve, in its normal position ready to operate and open the valve the moment the prop is removed from engagement with it. Hence the tripping prop serves as the holding device for the actuating-mechanism for
 10 the whistle-valve. The actuating-mechanism for the whistle-valve consists of an actuating-lever e and actuating-spring e^4 . Said actuating-lever is secured to a pivot-shaft e' having its bearings in the side plates of the apparatus, and which has a cord e^2 or equivalent attached to its extremity, which is connected with the whistle-valve lever or with a controlling-valve for the whistle. Said actuating-lever e has a
 15 downwardly extended leg e^3 forked at its lower end, and one arm of said fork rests upon the holding-device d^4 , so that the actuating-lever e is normally held in its elevated position by said holding-device, but
 20 when said holding-device is removed from beneath the leg e^3 , as shown in Fig. 4, the actuating-lever e will be released and will be immediately drawn down by the strong spring e^4 which is attached to it and the
 25 whistle-valve lever thereby operated to open the valve. The actuating-lever e also has a leg e^5 at its extremity, which, by striking a fixed part of the frame, limits its downward movement.
 30 The mechanism, thus described, which is released by the electro-magnet, will operate to open the whistle-valve as soon as the armature lever retracts, so that the whistle-valve will be opened and the blast started
 35 promptly upon the reception of the signal impulse. The blast will continue until the whistle-valve is closed, and it is herein designed to close it only at the end of a pre-determined period of time, and to then
 40 bring the timing-mechanism to rest promptly so that each blast will be of the same duration and will be operated under the same conditions, thereby securing the uniformity which is required for accuracy
 45 and distinctness.
 50 To close the whistle-valve its actuating mechanism is restored, that is to say, the actuating-lever e is raised against the force of its actuating-spring e^4 . To accomplish
 55 this result the shaft d' has secured to it a cam f , which serves as the restoring-device, which is located beneath the other arm of the forked end of the leg e^3 of the actuating-lever, and is adapted to engage said leg and
 60 lift the actuating-lever once during each

revolution of the shaft. Normally, the cam f occupies the position shown by dotted lines Fig. 3, it having just disengaged the leg, hence the actuating-lever will be lifted by the cam during the latter part of its rotation or just before it completes its rotation. 70

The shaft d' bearing the cam f is rotated by a timed motor-mechanism or train, so as to lift or restore the actuating-lever e and close the whistle-valve at the end of a predetermined period of time. The said train also operates to restore the holding device d^4 for said actuating mechanism, and also to restore the controlling-lever b , as 75 will be hereinafter described. As a motor-mechanism or train for thus rotating the shaft d' . I have herein shown a weight-driven or other power-driven shaft h bearing a ratchet wheel h' which engages a pawl h^2 , connected to the face of a toothed gear h^3 , which engages a pinion h^4 , secured to a shaft h^5 , bearing a toothed gear h^6 , which engages a pinion h^7 , secured to the shaft d' , and a toothed gear h^8 is also secured to said shaft d' which engages a pinion h^9 secured to a shaft h^{10} bearing the governor for controlling the speed of the train. 80

All of the shafts of the motor-mechanism have their bearings in the side plates of the frame or they may be otherwise supported. 95

As a governor I have provided a cross-bar h^{12} , see Fig. 8, mounted loosely on the shaft h^{10} and extended in opposite ways therefrom and bearing at its extremities fan-blades h^{13} . The cross-bar is formed with a hub h^{14} having a circular recess of conical form, adapted to frictionally engage a conical disk h^{15} which is secured to said shaft, and the cross-bar is engaged or acted upon by a spring h^{16} arranged on said shaft h^{10} between the cross bar and a nut on said shaft, and by means of said spring its hub h^{14} is held in permanent frictional engagement with the disk h^{15} by a yielding pressure which may be regulated by adjusting the nut. 100

When the shaft h^{10} starts from a position of rest the governor immediately begins to revolve with it and when said shaft suddenly ceases to revolve, by the stopping of the train, the governor continues to revolve for a short distance and thereby prevents too great a shock to the parts as the train stops. But the friction clutch which is herein provided between the governor and train also acts as a brake to quickly bring the governor to rest and is employed particularly for this purpose. Quickly stopping the train is an important factor in uniform timing the successive blasts, for, if the apparatus does not come to complete rest between each impulse of the signal, then the time elapsing between the end of the first blast and the beginning of the second blast, 115 120 125 130

or series of blasts, will be shorter than the time which elapses between the succeeding blasts of the series, for the reason that the governor of the train being in motion at the beginning of the second blast of the series will complete its second operation in a shorter period of time than if starting from a state of rest. For a like reason the length of the blast will vary. Heretofore in order to overcome this difficulty slow time for the alarms has been required, so that the variations would not be particularly noticeable, but a slow signal means serious delay to the fire department. With a friction brake the parts come to rest so quickly that they are ready to respond to the succeeding impulses in the shortest space of time which is ordinarily required between the blasts of the whistle, and the alarm need never be given a slow time to insure a uniform response or correct counting.

The motor-mechanism or train is released when the electro-magnet operates to disengage the controlling-lever b , to release the holding means for the actuating mechanism for opening the valve, and in practice is indirectly released by said electro-magnet, although, so far as my invention is concerned it is immaterial how it is released so long as it is released simultaneously with or at a predetermined time with respect to the releasing of the actuating mechanism for the whistle valve, in order that it may perform its functions of restoring said actuating-mechanism at the end of a predetermined period of time.

As herein shown, the locking-lever c^3 which holds the holding-device d^4 for the actuating mechanism for opening the whistle valve also acts to control the starting and stopping of the train, so that whenever the electro-magnet is operated and said actuating mechanism released and the whistle-valve opened, the train will be started and will continue the run, until it, in turn, restores said spring-actuated means and thereby closes the whistle-valve. To thus control the starting and stopping of the train the arm d , has a laterally projecting pin g which extends between two of the spokes of one of the gears of the train, as for instance, the toothed gear h^s , and when said arm is held at rest, by engagement with the locking-lever c^3 , the toothed gear will be restrained from rotation by one of its spokes engaging said pin g . Thus the pin g on the arm d serves as the holding device for the normally wound train. When the arm d is released, it is moved quickly by the spring d^2 far enough for the holding device d^4 to disengage the actuating-lever e , and for the holding device g to be thrust against the next spoke of the toothed gear h^s . Thus the spring actuated holding device d^4 is permitted or caused to operate independently

of the train, so as to release the actuating mechanism for the whistle valve and permit it to operate independently of the train to open the valve. The actuating-spring d^2 of the holding-device is attached to the toothed gear h^s , so that as said gear revolves said device will be turned with it on the same axis, and will make a complete revolution, but just before said toothed gear completes its revolution the cam f will raise the actuating-lever e , as shown in Fig. 6, in order that the holding-device d^4 may pass under one of the arms of the leg e^3 . As the holding-device completes its revolution its arm d engages the locking-lever and comes to rest. The train, however, continues to operate and revolve the gear-wheel h^s carrying the restoring-cam f with it from beneath the leg e^3 of the actuating-lever until the pin g on the arm d engages a spoke of the forwardly moving gear-wheel when the train ceases to operate. As the cam passes from beneath one arm of the leg e^3 , the other arm of said leg will be supported upon and by the holding-device d^4 which has been brought into position beneath it. While the train continues to operate after the arm d of the holding-device has engaged the locking-lever the actuating spring d^2 will be extended and thereby restored to its normal condition. Furthermore while the train is thus extending said actuating-spring, said spring exerts a retarding and cushioning effect upon the train, tending to bring it to rest quickly and also to lessen its shock, thereby serving as a buffer. As before stated, the locking-lever c^3 falls by gravity when permitted so to act, and as it was lifted by the controlling-lever b it will be permitted to fall when said controlling-lever is restored to its normal position, and to restore said controlling-lever an arm i is secured to its pivot-shaft b' , which extends downward into the path of movement of a cam i' , which is secured to the shaft d' , see Fig. 7, and in the normal position of the parts the arm i is free to move whenever the controlling-lever is disengaged, and just before the shaft d' completes its revolution said cam i' engages said arm i and lifts it, turning the shaft bearing the controlling-lever b , and thereby restoring said controlling-lever. It is immaterial just when the controlling-lever is restored so long as it is restored before the shaft d' has made a complete revolution, in order that it may be ready to be again released by the electro-magnet, for it is the time required for the shaft d' to make a certain portion of a revolution, in the particular construction herein shown, which determines the length of time each blast of the whistle shall continue.

Referring to Fig. 4, m represents the whistle-valve, and m' the operating-lever therefor, which is connected by the cord or

link e^2 , with the actuating-lever e of the apparatus, and said valve-operating-lever has connected to it a spring m^2 by which it is moved to close the valve.

5 From the foregoing it will be seen that while the several groups of elements are combined and arranged to operate conjunctively, being more or less dependent on each other for their operations, yet so far 10 as my invention is concerned I do not desire to limit it to the groups of elements thus constructed and arranged.

In the operation of the apparatus it will be noted that the blast of the whistle will 15 begin substantially simultaneously with the release of the train, and the time required for the train to overcome its inertia and run far enough to restore the actuating mechanism for the whistle valve, gives the 20 length of time required for the blast, and by utilizing the time required for the train to overcome its inertia in the timing of the blast the greatest efficiency will be obtained, as the time thus required is utilized in tim-

25 ing the blast and the momentum of the train in running is utilized in restoring the actuating mechanism for the whistle-valve. Furthermore, by connecting the actuating-spring of the holding-device to said train

30 in such manner that said holding-device is restored to normal by the train a cushioning effect is obtained when stopping the train. Furthermore, by connecting the governor with the train by a friction clutch,

35 the brake effect thereof is utilized to bring the governor to rest quickly, so that the train may be brought to a state of rest at the end of each blast, in order that it may be started from a state of rest at the begin-

40 ning of each blast. When thus constructed and arranged the whistle promptly responds to the signal impulses and the blasts are of uniform duration, and fast alarms from whistles are obtained. The train can be run 45 very fast and still give the proper length of blast, and the governor can be made very light, and but little power is required to operate the apparatus.

Having thus described my invention, what 50 I claim as new and desire to secure by Letters Patent is:—

1. In a whistle-blowing machine, the combination of actuating-mechanism for the whistle-valve, means for holding said actuating-mechanism, a timed restoring-train, for restoring said actuating-mechanism at the end of a predetermined period of time, which is normally disengaged from said actuating-mechanism, means for holding 55 said restoring-train and means for controlling the operation of the holding-means for said actuating-mechanism and the holding-means for said restoring-train including an operating-magnet, whereby said actuating-mechanism is released and permitted to op-

erate the whistle-valve quickly and is subsequently restored by said train, substantially as described.

2. In a whistle-blowing machine, the combination of a normally wound timing-mechanism, holding-means therefor, electro-magnetically controlled means to release said holding-means, actuating-mechanism for the whistle-valve, holding-means for said actuating-mechanism also arranged to be released by said electro-magnetically controlled means and simultaneously with the aforesaid holding-means, whereby the actuating-mechanism is permitted to operate the whistle-valve to begin its blast while the timing-mechanism is overcoming its inertia, and means operated by the timing-mechanism for restoring said actuating-mechanism at the end of a predetermined period of time, and also both holding-means, so that the blast which begins while the timing-mechanism is overcoming its inertia is continued while the timing-mechanism is running, substantially as described. 70 75 80 85

3. In a whistle-blowing machine, the combination of actuating-mechanism for the whistle-valve, a timed restoring-train for restoring said actuating-mechanism at the end of a predetermined period of time, holding devices for said actuating-mechanism and said restoring-train respectively, both holding-devices being operable independently of the timed restoring-train to release respectively the actuating-mechanism and the timed restoring-train, and an electro-magnet controlling the operation of both holding devices, whereby said actuating-mechanism is released and permitted to operate the whistle-valve quickly and is subsequently restored by said train, substantially as described. 90 95 100 105

4. In a whistle-blowing machine, the combination of actuating-mechanism for the whistle-valve, a timed restoring-train for restoring said actuating-mechanism at the end of a predetermined period of time, holding-devices for said actuating-mechanism and said restoring-train, respectively, both holding-devices being operable independently of the timed restoring-train to release, respectively, the actuating-mechanism and the timed restoring-train, and electrically controlled means for operating both holding-devices simultaneously, whereby the actuating-mechanism is released and permitted to operate the whistle-valve quickly and is subsequently restored by said train, substantially as described. 110 115 120

5. In a whistle-blowing machine, the combination of a timing-mechanism, a spring-controlled actuating-mechanism for the whistle-valve, means for holding said actuating-mechanism set in condition to operate independent of said timing-mechanism, restoring-means for said actuating-mechanism 125 130

and said holding-means operated by said timing-mechanism, said actuating-mechanism being moved by its controlling spring into position to be engaged by its restoring-
means, electro-magnetically controlled means to control the operation of the means for holding the actuating-mechanism and also controlling the starting of the timing mechanism and restoring-means for said electro-magnetically controlled means, also operated by said timing-mechanism, substantially as described.

6. In a whistle-blowing machine, the combination of actuating-mechanism for the whistle-valve, a timing-mechanism for controlling said actuating-mechanism, spring-actuated holding-devices for holding said actuating-mechanism and said timing-mechanism, respectively, in condition to operate, electrically controlled means for controlling the operation of said holding-devices, and means operated by the timing-mechanism for restoring said actuating-mechanism at the end of a predetermined period of time and for restoring said controlling-means and for placing the actuating-mechanism under the control of its holding-device, substantially as described.

7. In a whistle-blowing machine, the combination of actuating-mechanism for the whistle-valve, a timed restoring train for restoring said actuating-mechanism at the end of a predetermined period of time, spring-actuated holding-devices for holding said actuating-mechanism and said restoring-train, respectively, in condition to operate, a locking-lever adapted to be operated to release both holding-devices simultaneously, whereby the actuating-mechanism and the restoring-train are simultaneously released, and electrically controlled means for operating said locking-lever, substantially as described.

8. In a whistle-blowing machine, the combination of a spring-actuated lever connected with the whistle-valve, a timed restoring-train for said actuating-lever, nor-

mally disengaged therefrom but movable into engagement therewith when the latter is released and occupies its abnormal position, spring-actuated holding-devices for said actuating-lever and said restoring-train, respectively, and electrically controlled means for operating said holding devices, whereby said actuating-lever is released and permitted to operate the whistle-valve quickly and is subsequently restored by said train, substantially as described.

9. In a whistle-blowing machine, the combination of a spring-actuated lever connected with the whistle-valve, electrically controlled means for normally holding said lever against the action of its actuating-spring and for releasing it upon a change in the electric-circuit connected therewith, a timed restoring-train normally disengaged from said actuating-lever, for engaging said actuating-lever in its abnormal position and for restoring it at the end of a predetermined period of time, and means for holding said restoring-train, said holding-means being operated to release said restoring-train upon the release of said actuating-lever, substantially as described.

10. In a whistle-blowing machine, the combination of actuating-mechanism for the whistle-valve, a timed restoring-train for restoring said actuating-mechanism at the end of a predetermined period of time, an electrically controlled holding-device for said actuating-mechanism, and a holding-device for said restoring-train connected with the aforesaid holding-device, whereby said actuating-mechanism is released and permitted to operate the whistle-valve quickly and is subsequently restored by said train, substantially as described.

In testimony whereof, I have signed my name to this specification, in the presence of two subscribing witnesses.

FREDERICK W. COLE.
